(57) **CLAIM**

The ornamental design for a construction toy with interlocking bricks as shown and described.

DESCRIPTION

FIG. 1 is a top perspective view of the construction toy with interlocking bricks showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom perspective view thereof.

The broken lines immediately adjacent to the shaded areas depict boundaries, while all other broken lines depict environment. The broken lines form no part of the claimed design.
